(57) **CLAIM**

The ornamental design for a dart board, as shown and described.

DESCRIPTION

FIG. 1 is a front perspective of the dart board showing my new design;

FIG. 2 is a front plan view thereof;

FIG. 3 is a left side elevational view thereof;

FIG. 4 is a top view thereof;

FIG. 5 is a bottom view thereof;

FIG. 6 is a right side elevational view thereof; and,

FIG. 7 is a rear plan view thereof.

The broken lines in the drawings illustrate the portions of the design that form no part of the claim.
